SHUTTLE SLIDER

Louis H. Morin, Bronx, N. Y., assignor of one-half
to Davis Marinsky, Bronx, N. Y.

Application November 24, 1942, Serial No. 466,740

16 Claims. (Cl. 24—205)

This invention relates to separable fasteners employing sliders movable along stringers to couple and uncouple the same. More particularly, the invention relates to a duplex slider structure which is termed a shuttle body movable along a pair of stringers to maintain constant coupling engagement of the stringers while maintaining an opening of predetermined contour and size within the slider body, thereby facilitating movement of this opening along the stringers from one end to the other end thereof.

The novel features of the invention will be best understood from the following description when taken together with the accompanying drawing, in which certain embodiments of the invention are disclosed, and in which the separate parts are designated by suitable reference characters in each of the views; and in which:

Fig. 1 is a plan view of one form of shuttle slider which I employ with parts of the construction broken away and in section.

Fig. 2 is a cross section on the line 2—2 of Fig. 1.

Fig. 3 is a view similar to Fig. 1, but showing only the slider and illustrating a modification.

Fig. 4 is a longitudinal sectional view on the line 4—4 of Fig. 3.

Fig. 5 is an enlarged sectional view of one end portion of a shuttle slider illustrating the mounting of independent slider elements at end portions of the shuttle body.

Fig. 6 is a longitudinal sectional view through another form of shuttle slider with parts of the construction broken away and omitting other parts, and

Fig. 7 is a partial section on the line 7—7 of Fig. 6.

In certain uses and adaptations of separable fasteners of the kind employing stringers coupled and uncoupled by a slider movable along the stringers, there are occasions where it is desirable to move a member of some type or kind between the stringers or through the opening controlled by the stringers while maintaining stringer ends in closed position, for example in providing an elongated slot or opening in a supporting body, for example, a gun slot, and in moving the barrel of a gun longitudinally of the slot or opening while keeping the slot substantially closed at points other than the position occupied by the gun barrel.

For purposes of the kind generally indicated above, I provided what I term a shuttle slider, that is to say, an enlarged slider body having an opening therein shaped to receive the member.

For example, the gun barrel and said body having contracted end portions so shaped as to freely couple and uncouple the links or scoops of the stringers of a separable fastener.

5 In Figs. 1 and 2 of the drawing is shown one adaptation of the invention and in these figures 10 and 11 represent the two stringers which are to be coupled and uncoupled by the shuttle slider body 12. In the present construction the 10 links or scoops 13 of the stringer 11 and 10 are of the double action type, that is to say, are capable of being coupled and uncoupled by reverse positioning of two conventional sliders on a pair of stringers. In other words, a single slider may be positioned in either of two directions or positions on the slider and freely operated to couple and uncouple the stringers.

The stringers 10 and 11 are secured to suitable supporting strips 14, 15 employed to attach the 20 stringers to supports which would generally define an elongated slot or opening. In other words, a slot in which a gun barrel would be free to move.

The slider body as disclosed in Figs. 1 and 2, comprises an inner ring like member 16, having contracted projecting ends 17, which ends take the place of the parting webs of conventional slider bodies and are employed in the present construction to separate and divert the links of the opposed stringers into channels 18 and 19, 30 arranged at opposite sides of the shuttle body 12.

The channels 18 and 19 are partially formed by corresponding top and bottom plates 20, 21, which are secured to the ring like body 16 as 35 indicated at 22 and project beyond the body 16 and have at their free edges inturned flanges 23.

It will appear from a consideration of Fig. 2 of the drawing that the flanges 23 of one plate, the plate 20, are spaced from the flanges of the other plate 21, which provide channel openings for permitting free passage of the stringer tapes therethrough. The flanges 23 conform generally to the outer peripheral contour of the body 16 and 45 extended beyond the projecting webs 17 in contracted end portions 24, and 25. These end portions may each be said to comprise a conventional slider structure, thus producing of the complete shuttle body a duplex slider. The channels 18 and 19 merely serve as means for guiding the links of the stringers from one slider end to the other.

At this point, attention is directed to the disclosure in Fig. 5 of the drawing, in which a shuttle body 26 substantially of the same construction

as that shown in Figs. 1 and 2 is employed but instead of depending upon the flanges 23 of the plates 20, 21 to produce the slider ends 24, 25, actual conventional sliders 27 are freely seated in slider receiving sockets 28 at end portions of the shuttle body 26.

With this construction the web 29 of the slider 27 will form an extension to a reduced and rounded end 30 on the projection of the ring like body 31. The flanges 32 of the shuttle body 26 will also be offset outwardly to accommodate the flanges 33 of the slider 27. It will be understood that both ends of the shuttle body 26 will be of the same construction.

In Fig. 5, portions of two stringers 34 and 35 are indicated, and these stringers have double action scoops or links 36 which differ in construction from the links 13. As these links form no specific part of the present invention, no detailed description thereof is given.

In Fig. 3 of the drawing is shown a slight modification of the construction illustrated in Figs. 1 and 2, and this modification comprises simply making the complete shuttle body 37 of two similar end portions hinged together as seen at 38, so that the end portions are free to swing on the pivots of the hinges to compensate for different curvatures of a support in connection with which the shuttle body may be mounted.

Here it is to be pointed out that in some instances the shuttles may travel in a straight path when the slotted or apertured supports for the stringers are straight. In other instances, the support will have a more or less constant curvature, in such cases this curvature will be provided in the shuttle body. However, where the curvature may change throughout the length of the passage of the shuttle body by pivoting the end portions thereof, these ends will compensate at least to some degree for the differences in curvature.

The hinge construction or pivoting of the separate ends of the shuttle 37 may be accomplished in many ways, however, in the accompanying drawing, and as will be seen in Fig. 4, the hinges 38 may simply be disposed upon one side surface, preferably the convexed surface 39 of the shuttle body.

In Figs. 6 and 7 of the drawing is illustrated another adaptation of the invention and this differs primarily from the structures shown in Figs. 1 to 5 inclusive, in the fact that the entire shuttle body 40 is composed of two interfitting parts rather than from a ring in two side plates.

With this construction both parts 41 and 42 will include inner ring portions made to seat one upon the other, the ring portion of the part 41 being rounded, as seen at 43 to facilitate free movement of an article or member such as a gun barrel 44 therein. Whereas the ring portion of the part 42 has an extending annular skirt 45, which forms a support for a leather or other boot 46, one end of which is clamped to the skirt 45 as indicated at 47 and the other end clamped to the barrel 44 as indicated at 48.

The contracted ends of the shuttle body 40 are fashioned to form between the parts 41 and 42 sockets 49 and 50 to receive conventional sliders as, for example, the slider 27 of Fig. 5. The sockets 49 and 50 also preferably include rounded recesses 51 which are adapted to receive projections 52 on sliders to provide what might be termed a free pivotal mounting of the sliders in the sockets 49 and 50. One slider 53 is indi-

cated in section in the socket 49 but the slider of the socket 50 has been omitted.

The two parts 41 and 42 are riveted or otherwise secured together as indicated at 54. Extending from the socket ends 49 and 50 along the sides of the shuttle body 40 are channels 55 so shaped as to angularly dispose the links 56 of stringers 57 at the wide sides of the shuttle body, thereby facilitating a closer fit and operation of the shuttle body in the aperture or opening of a support, and also minimizing the flexure of the stringer and supporting tapes, as will be apparent from a consideration of Fig. 2 of the drawing, in which figure an approximate folding 15 of the tape is illustrated as would be the case when the links extend perpendicularly to the surface of the shuttle sides.

It will, of course, be apparent that in different uses and adaptations of the invention the general shape and contour of the shuttle body will be varied to suit, first the member to be disposed therein, and then the support in connection with which the stringers are mounted. Furthermore, the channelled guide ways arranged 25 between what may be termed the slider or coupling ends of the shuttle may also be modified to suit the different adaptations and uses of the invention.

It will be understood that the boot 46 provides a means for effecting a seal between the shuttle body and the barrel 44 or other member disposed therein. Sufficient flexibility will be provided in the rubber, canvas or other boot to care for flexure of the shuttle body in traveling 35 the full length of the stringers employed.

Considering the few adaptations of the invention which are disclosed for illustrative purposes, it will be apparent that the invention may be said to comprise the use of a device having spaced sliders or slider ends joined by a pair of spreading guide channels, employed for the purpose of guiding fastener stringers between the spaced sliders and also to spread the stringers sufficiently to clear the member which is movably disposed therebetween.

Having fully described my invention, what I claim as new and desire to secure by Letters Patent is:

50 1. A device for coupling and uncoupling the stringers of separable fasteners, said device comprising a slider body having a large opening centrally thereof, opposed end portions of said body being contracted to couple the stringers of separable fasteners at said end portions of said body, and means intermediate said end portions for guiding the separated stringers in predetermined paths at opposed sides of the opening formed in said slider body and collectively in a curved path conforming to the contour of a curved support surface.

55 2. A device for coupling and uncoupling the stringers of separable fasteners, said device comprising a slider body having a large opening centrally thereof, opposed end portions of said body being contracted to couple the stringers of separable fasteners at said end portions of said body, means intermediate said end portions for guiding the separated stringers in predetermined separate paths at opposed sides of the opening formed in said slider body, said last named means comprising channels in which the links of the stringers are free to pass, and the first named end portions of said slider body having webs guiding 70 opposed stringers into the side channels of said

body and collectively in a curved path conforming to the contour of a curved support surface.

3. A device for coupling and uncoupling the stringers of separable fasteners, said device comprising a slider body having a large opening centrally thereof, opposed end portions of said body being contracted to couple the stringers of separable fasteners at said end portions of said body, means intermediate said end portions for guiding the separated stringers at opposed sides of the opening formed in said slider body, said last named means comprising channels in which the links of the stringers are free to pass, the first named end portions of said slider body having webs guiding opposed stringers into the side channels of said body, said body being composed of separate parts, and means securing said parts together and adapted to permit relative movement of said parts to enable said body to adapt its contour to that of a curved support surface.

4. A device for supporting stringers of separable fasteners in spaced relationship to each other while maintaining end portions of the stringers in coupled relationship, said device comprising a large slider body having an opening centrally thereof, said portions of said body having channels for receiving and guiding the links of the stringers when supported, by said body, in predetermined paths in spaced relationship to each other, end portions of said body being contracted, and means at said end portions for coupling and uncoupling the links of the stringers and for guiding the links into said channels and means intermediate said ends to direct said stringers collectively in a curved path conformed to the curvature of a support surface.

5. A device for supporting stringers of separable fasteners in spaced relationship to each other while maintaining end portions of the stringers in coupled relationship, said device comprising a large slider body having an opening centrally thereof, side portions of said body having channels for receiving and guiding the links of the stringers when supported, by said body, in spaced relationship to each other, end portions of said body being contracted, means at said end portions for coupling and uncoupling the links of the stringers and for guiding the links into said channels, and said last named means comprising housings within which slider members are freely supported in connection with the contracted end portions of said body.

6. A device for supporting stringers of separable fasteners in spaced relationship to each other while maintaining end portions of the stringers in coupled relationship, said device comprising a large slider body having an opening centrally thereof, side portions of said body having channels for receiving and guiding the links of the stringers when supported, by said body, in spaced relationship to each other, end portions of said body being contracted, means at said end portions for coupling and uncoupling the links of the stringers and for guiding the links into said channels, and means centrally of the side portions of said body for hingedly coupling the end portions thereof to provide relative movement of said end portion.

7. A device for supporting stringers of separable fasteners in spaced relationship to each other while maintaining end portions of the stringers in coupled relationship, said device comprising a large slider body having an opening centrally thereof, side portions of said body having channels for receiving and guiding the links of the

stringers when supported, by said body, in spaced relationship to each other, end portions of said body being contracted, means at said end portions for coupling and uncoupling the links of the stringers and for guiding the links into said channels, said body being composed of separate parts, means coupling said parts, and one of said parts having a sleeve portion bordering the opening in said body.

10. A device for supporting stringers of separable fasteners in spaced relationship to each other while maintaining end portions of the stringers in coupled relationship, said device comprising a large slider body having an opening centrally thereof, side portions of said body having channels for receiving and guiding the links of the stringers when supported, by said body, in spaced relationship to each other, end portions of said body being contracted, means at said end portions for coupling and uncoupling the links of the stringers and for guiding the links into said channels, the opening in said body being adapted to receive a member movable longitudinally of the stringers, and flexible means forming a seal between said member and of said body.

15. A device for supporting stringers of separable fasteners in spaced relationship to each other while maintaining end portions of the stringers in coupled relationship, said device comprising a large slider body having an opening centrally thereof, side portions of said body having channels for receiving and guiding the links of the stringers when supported, by said body, in spaced relationship to each other, end portions of said body being contracted, means at said end portions for coupling and uncoupling the links of the stringers and for guiding the links into said channels, the opening in said body being adapted to receive a member movable longitudinally of the stringers, and flexible means forming a seal between said member and of said body.

20. A device for supporting stringers of separable fasteners in spaced relationship to each other while maintaining end portions of the stringers in coupled relationship, said device comprising a large slider body having an opening centrally thereof, side portions of said body having channels for receiving and guiding the links of the stringers when supported, by said body, in spaced relationship to each other, each of said sliders comprising a channelled member having diverging channels at one end contracted to a single channel at the other end thereof, the contracted ends of said sliders being directed outwardly at the ends of said body, and said body having stringer guide channels registering with the diverging channels of both sliders, said channels being shaped to support the links of the stringers in a position angular to the normal coupling position thereof.

25. A device for supporting stringers of separable fasteners in spaced relationship to each other while maintaining end portions of the stringers in coupled relationship, said device comprising a large slider body having an opening centrally thereof, side portions of said body having channels for receiving and guiding the links of the stringers when supported, by said body, in spaced relationship to each other, each of said sliders comprising a channelled member having diverging channels at one end contracted to a single channel at the other end thereof, the contracted ends of said sliders being directed outwardly at the ends of said body, and said body having stringer guide channels registering with the diverging channels of both sliders, said body being composed of separate parts, and means for securing said parts together, said parts having recessed portions forming a housing within which said sliders are supported when the parts are secured together.

30. A device for supporting stringers of separable fasteners in spaced relationship to each other while maintaining end portions of the stringers in coupled relationship, said device comprising a large slider body having an opening centrally thereof, side portions of said body having channels for receiving and guiding the links of the stringers when supported, by said body, in spaced relationship to each other, each of said sliders comprising a channelled member having diverging channels at one end contracted to a single channel at the other end thereof, the contracted ends of said sliders being directed outwardly at the ends of said body, and said body having stringer guide channels registering with the diverging channels of both sliders, said body being composed of separate parts, means for securing said parts together,

and end portions of said body having housings within which the sliders are freely supported.

12. The combination with two conventional sliders employed for coupling and uncoupling stringers of separable fasteners, of a large apertured body, having means at end portions thereof for supporting said sliders against displacement therefrom and in wide spaced relationship to each other, each of said sliders comprising a channelled member having diverging channels at one end contracted to a single channel at the other end thereof, the contracted ends of said sliders being directed outwardly at the ends of said body, said body having stringer guide channels registering with the diverging channels of both sliders, said body being composed of separate parts, means for securing said parts together, end portions of said body having sockets in which the sliders are freely supported, and one part of said body having a projecting sleeve portion bordering the aperture of said body.

13. A shuttle slider for stringers of separable fasteners, said slider comprising a large apertured body having spaced channels bordering opposed sides of the aperture in said body, said channels converging to single channels at opposite contracted end portions of said body, and webs inwardly of said contracted ends dividing the single channels into said side channels, said body having an arcuate contour adapted to conform to the curved surface of a support.

14. A shuttle slider for stringers of separable fasteners, said slider comprising a large apertured body having spaced channels bordering opposed sides of the aperture in said body, said

channels converging to single channels at opposite contracted end portions of said body, webs inwardly of said contracted ends dividing the single channels into said side channels, and means centrally of the side portions of said body providing relative movement of the contracted end portions of said body.

15. A device for supporting stringers of separable fasteners in spaced relationship to each other while maintaining end portions of the stringers in coupled relationship, said device comprising a large slider body having an opening centrally thereof, side portions of said body having channels for receiving and guiding the links of the stringers when supported, by said body, in spaced relationship to each other, end portions of said body being contracted, means at said end portions for coupling and uncoupling the links of the stringer and for guiding the links into said channels, and said channels at opposite sides of said body supporting the links of the stringers in a position angularly to the normal coupling position thereof.

16. The combination with spaced sliders arranged upon stringers of separable fasteners employing double action scoops, of means coupling and supporting said sliders in spaced relationship to each other, said means also including means supporting and guiding uncoupled stringers in predetermined paths in spaced relationship to each other intermediate said spaced sliders in the movement of the sliders along said stringers and collectively in a curved path conforming to the contour of a curved support surface.

LOUIS H. MORIN.

CERTIFICATE OF CORRECTION.

Patent No. 2,344,049.

March 14, 1944.

LOUIS H. MORIN.

It is hereby certified that error appears in the printed specification of the above numbered patent requiring correction as follows: Page 1, second column, line 38, for "apepar" read --appear--; page 3, first column, lines 1 and 2, strike out the words "and collectively in a curved path conforming to the contour of a curved support surface" and insert the same after "body" and before the comma, page 2, second column, line 71; and that the said Letters Patent should be read with this correction therein that the same may conform to the record of the case in the Patent Office.

Signed and sealed this 23rd day of May, A. D. 1944.

Leslie Frazer

(Seal)

Acting Commissioner of Patents.
